UNITED STATES PATENT OFFICE

JOSEPH RAH, OF CHICAGO, ILLINOIS, ASSIGNOR TO G. & W. ELECTRIC SPECIALTY COMPANY, OF CHICAGO, ILLINOIS, A CORPORATION OF ILLINOIS

OIL SWITCH

Application filed April 7, 1927. Serial No. 181,667.

The invention pertains to an oil switch and more particularly to such a switch used for the sectionalizing of a line if and when there is some trouble in a certain section of said line.

It has formerly been the custom in repair, installation or service conditions to provide a switch of some type for sectionalization or transmission but it has been found that due to imperfect contact of the switch bar or the unsatisfactory mode of contact, there may be faulty delivery of the current, or the parts of the switch may become damaged causing the whole line to be put in disuse with the attendant inconvenience.

It is therefore an object of this invention to provide a switch of such character that there is always proper contact between the switch and the cable lead terminals.

It is another object to provide a switch that is self-aligning.

It is a further object to provide contact members for the cable lead terminals of such character that any arcing between the switch and the terminals upon a breaking of the connection, will not burn out the contact or cable terminals.

It is a further and more specific object to provide terminal and switch shoes of such form as to insure a perfect and rubbing contact between the switch and the shoes.

Other and more specific objects will occur from the detailed description given.

In the drawings—

Figure 1 is an elevation, partly in section, of the oil switch, showing the contact arm in open or inoperative position; and

Figure 2 is a section of Figure 1 taken substantially at right angles thereto, showing particularly the operating mechanism for the switch arm.

In general, A is an oil switch having a lower oil carrying receptacle B. C and E are the usual cables provided with terminals which are adapted to be connected by the switch arm or block D.

More particularly, 1 represents the oil switch housing, at the bottom of which the insulating oil carrying receptacle 2 is disposed having the oil plug 3 therein. The

sides and bottom of said receptacle are insulated by suitable means 4 and 5. The bottom is provided with insulating partitions 6 which are disposed so as to sectionalize the plurality of switch blocks provided in the oil receptacle and to similarly separate the corresponding leads C and E provided in the receptacle. Any number of cable leads 7 may be provided, connected through suitable connections which form no particular part of the invention, to terminals or conductors 8 disposed in insulating tubes 9 extending between the upper part of the housing and the lower oil containing receptacle through the insulating base 30. Each terminal is provided with a flattened lower portion provided with suitable fastening means 11 for a supporting spring 12 to which a shoe 13 is attached by any suitable connection 19, each shoe preferably extending slightly into the path of movement of the switch block.

The terminal is provided with a lug 20 which serves as positioning means for a spring 14 disposed between the terminal and the shoe, the head of connection 19 also providing positioning means for said spring. Limiting means 15 may be provided between the shoe and the terminal, a suitable recess 16 being provided in the shoe for receiving the bent end of said limiting means, which may conveniently be in the form of a tapped elbow or L-shaped bar. The shoe is provided with a flat switch engaging portion 17 and an arcuate nose 18 for guiding the switch block to final operative position. An arc spring 21 may be provided between the terminal and the shoe so that when contact is made or broken from the shoe and the switch block, the shoe-holding spring 12 will not be burned out due to any arcing action between the switch block and the shoe.

The switch block is of general I-section, provided with the shoe contacting ends 23 which are provided with arcuate noses, said contacting portions being connected by a body portion 22 hinged at or near the center thereof to an insulating link 26 which is pivoted to the bell-crank 27. Any other lead, such as 25, which may enter the oil switch through the top and through the correspond-

ing tube such as 9, is provided with a corresponding terminal with a shoe similar to the shoe 13, but facing it for electrical connection thereto by the contact block D. On either 5 side of the switch blocks and disposed between the block and the shoe spring and terminal connection, insulation 24 may be provided extending to a position adjacent the shoe. The switch operating mechanism 10 consists of a key receiving means 29 which extends through the receptacle housing and which, through the arm 28, operates the bell crank 27 which is connected to the switch block D through the insulating link 26. 15 Insulating base 30 is provided between the oil receptacle and the terminal receiving portions of the oil switch housing, the same being apertured to receive insulating sleeves 9. It has been found convenient to form the receptacle in a plurality of parts, such that the wiping sleeve, the terminal receiving portion, and the oil receptacle are all separate so that the connections of the leads, the switch, the terminals and the shoes are absolutely accessible. 20 25

In operation, it will be understood that the switch block D is in contact with the shoes 13 and that thereby the cable leads 7 and 25 are in electrical connection. It will be understood that any number of said oil switches 30 may be provided between the feeder and sections of the lines and if any trouble occurs in the line, by moving the switch block to inoperative position, that section may be cut 35 out while the rest of the line will still be in use. When contact is desired between the shoes, it is only necessary to move said shoes by applying a key to the means 29 and operating said switch block through the bell 40 crank 27. It will be seen that should the switch block first contact one shoe, due to its pivotal connection to the link 26 and the flexible mounting of the other shoe, the contact made between said shoes and the switch 45 block will still be perfect due to the action of guiding noses on the shoes and switch block which cause a wedging action, and the rubbing contact effected between said switch block and said shoes when the block is pulled 50 into final operative position.

I do not wish to be limited by the parts or form of the device shown, which it is to be understood are only by way of illustration and not limitation, as other and various forms of 55 the device will of course occur to those skilled in the art.

I claim:

In a switch the combination of a casing including an oil receptacle, fixed electrodes extending into said oil receptacle below the oil level thereof, contact shoes, means resiliently connecting said contact shoes and electrodes, resilient means disposed between said shoes and electrodes for urging said shoes away 65 from said electrodes, a contact block having

contact shoes thereon, means for moving said contact block whereby said shoes contact said first named shoes for electrically connecting said electrodes, said shoes having noses shaped to guide said shoes into rubbing contact, arcing leaves carried by said electrodes and aligned with the noses of the associated shoes, and means on said electrodes cooperating with the shoes carried thereby for limiting the position thereof and presenting said shoes for flat surface engagement by the shoes of said contact block.

Signed at Chicago, Illinois, this 2nd day of April, 1927.
